Patented Dec. 18, 1923.

Des. 63,590

UNITED STATES PATENT OFFICE.

ADOLF B. SCHLEICHER, OF LOS ANGELES, CALIFORNIA.

DESIGN FOR A PNEUMATIC TIRE.

Application filed May 29, 1922. Serial No. 2,466. Term of patent 7 years.

To all whom it may concern:

Be it known that I, ADOLF B. SCHLEICHER, a citizen of the United States, residing at Los Angeles, in the county of Los Angeles and State of California, have invented a new, original, and ornamental Design for Pneumatic Tires, of which the following is a specification, reference being had to the accompanying drawing, forming part thereof.

Figure 1 is a face view of a pneumatic tire provided with a tread embodying my design.

Fig. 2 is a cross section taken on a line indicated by 2-2 in Fig. 1.

I claim:

The ornamental design for a pneumatic tire as shown.

Signed at Los Angeles, California, this 27th day of April, 1922.

ADOLF B. SCHLEICHER.

Witnesses:

E. F. HILLERDAHL,
HERMAN HAUPT.
